CLAIM

What is claimed is the ornamental design for a steering wheel horn button, as shown and described.

DESCRIPTION

FIG. 1 is a perspective view of a first embodiment of a steering wheel horn button, showing the new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof;

FIG. 5 is a bottom plan view thereof;

FIG. 6 is a perspective view of a second embodiment thereof, a button portion thereof illustrated in a depressed position;

FIG. 7 is a front elevational view thereof, the button portion illustrated in the depressed position;

FIG. 8 is a rear elevational view thereof, the button portion illustrated in the depressed position;

FIG. 9 is a left-side elevational view thereof, the button portion illustrated in the depressed position, the right-side elevational view being a mirror image thereof;

FIG. 10 is a top plan view thereof; and,

FIG. 11 is a bottom plan view thereof.

The broken lines showing a finger in FIG. 6 and attachment hardware in FIGS. 5 and 11 are included for the purpose of illustrating the invention in use, and form no part of the claimed design.
